his Attorneys.

UNITED STATES PATENT OFFICE.

KARL W. P. REECE, OF ROXBURY, MASSACHUSETTS.

KNITTING-NEEDLE.

1,261,853.

Specification of Letters Patent.

Patented Apr. 9, 1918.

Application filed September 18, 1917. Serial No. 191,203.

To all whom it may concern:

Be it known that I, KARL W. P. REECE, a citizen of the United States of America, and resident of Roxbury, in the county of 5 Suffolk and State of Massachusetts, have invented new and useful Improvements in Knitting-Needles, of which the following is a specification.

This invention relates to knitting needles 10 for hand knitting. The instrument usually employed for articles knit in shaped or unshaped flat breadths, as distinguished from articles knit in tubular form, has heretofore been made as an integral uniformly cylindrical shank of bone, ivory, wood, celluloid or metal having a blunt point and provided with a button or head relied upon to keep the loops of the last course or row of loops knit, which are impaled upon the needle 15 as formed, from slipping off the head end of the needle. The operation, as well known, comprises pulling a new course of loops one by one through the previous course with the blunt point of another similar needle 20 upon which the loops of the new course are strung as they are formed. A complete course or row of loops across the article is thus held on a needle when the last loop is knit through and discharged from the needle 25 from which the previous course is being taken off.

When making many different kinds of garments or articles it is necessary to cease knitting at some part of a course which is 30 subsequently to be joined to following parts of the fabric by knitting again through these loops, but which can not be so joined until a separate part of the fabric is finished, as when a neck-opening is to be left 35 in a garment having a back and front knit in integral succession. In this case and in many other situations it has heretofore been customary to take off the loops of the part of a course at which knitting is temporarily 40 suspended on to a third instrument, so as to release the point of the needle then carrying the loops to permit making the other part of the garment. It requires time, care and skill to remove part of 45 a course of loops and put them on another instrument (such as the safety-pin commonly employed) and thereafter take them back in the right order on the operating needle. I have therefore devised trans- 50 fer means for locking the terminal course or part of the terminal course of a garment

permitting the removal of the loops of this course from the needle on which they were formed, comprising a needle formed in two or more sections which can be disengaged 60 and again engaged while carrying the desired number of impaled loops in such a manner as to permit the loops to be slid from one section to another section.

Further objects of my invention are to 65 provide a knitting needle having a transfer end or section from and to which the loops can be slipped readily in the order in which they are formed and strung upon the needle, the device providing for the easy re- 70 moval of the end or transfer section of the needle and for preventing the loops on the transfer section from accidentally slipping therefrom.

Another object of my invention is to pro- 75 vide a genus of constructions for the general purpose above described which shall be cheap, durable and effective.

Referring now to the accompanying drawings:—

Figure 1 is an elevation of one form of the needle corresponding to my invention and including a fragmentary showing of fabric loops strung upon the needle;

Fig. 2 is a fragmentary view separately 85 illustrating the removable transfer section of said needle and a cap therefor;

Fig. 3 is a view similar to Fig. 1 illustrating a modified form of needle;

Fig. 4 is an elevation of a transfer sec- 90 tion adapted to be used with the needle shown in Fig. 3;

Fig. 5 is an enlarged longitudinal section, and Fig. 6 a detail illustrating a tubular metallic needle corresponding to my invention; 95

Figs. 7, 8 and 9 are detail longitudinal sections illustrating different modified forms of joints between transfer section and needle-shank, and transfer section and temporary head, of needles corresponding to my 100 invention;

Fig. 10 is a modification illustrating an integral-head form of transfer section for a needle adapted to some classes of fabric; and

Fig. 11 illustrates diagrammatically one 105 operation in which the transfer section is particularly useful.

As shown in Figs. 1 and 2, a cylindrical shank 1 having a blunt point 2 is provided 110 with a transfer section 3 joined to the shank 1 at 4. In the form shown in said figure

the joint at 4 may comprise an integral reduced extension 5 of the shank threaded into an axial opening in the section 3.

The section 3 carries a permanent head 6 of any desired form, and may be provided with a screw-threaded hole 7 into which a head 8 for the section 3 having an integral threaded extension 9 is adapted to be screwed.

10 As indicated in Fig. 1, the loops 10 of the last course of the fabric are threaded as formed on the shank 1, and all or the desired part of the loops 10 may be slipped on to section 3, which should be long enough 15 to hold in a compressed state the desired number of loops. If knitting is to be suspended on the loops thus placed on the section 3 the needle is separated at the joint 4 and a temporary head 8 is removed from 20 the head 6 and screwed into the other end of the section 3.

A temporary head 11 for the needle section 1 having a threaded opening 12 may if desired be carried on a threaded stud 13 25 of the head 8. Usually I prefer to provide an additional section 3 which can be placed on the shank 1 whenever a section 3 is removed from the shank 1 with suspended loops upon it.

30 It will be understood that the screw joints mentioned are interchangeable, all being the same size. When the material of the needle is of wood, bone, celluloid or the like I prefer to make the male members of the screws 35 of separate metallic pieces.

As shown in Figs. 3 and 4, the shank 1 may be provided with an extension 15 having a removable head 17 suitably held as by the screw joint 18. When loops are to be 40 transferred from a needle of this form the head 17 is unscrewed and a headed transfer section 16 screwed on in its place, and the transfer loops are then removed on the section 16, which may be provided with a temporary head 19 to hold the loops. It will 45 be observed that the needle 1, 15 is still separable at the joint 4 to permit suspending a further series of loops by removing the section 15. In any of the forms of my device 50 I may so divide the needle in several places for this purpose.

Knitting needles made according to my invention may be constructed in any durable and satisfactory manner. As shown in Fig. 55 5 and Fig. 6 for instance, a point section 20 of any desired material such as celluloid or metal may be fastened into the end of a tubular section 21 of thin and light metallic tubing, the shank 21 being furnished with 60 a transfer section or extension 22 of similar tubing, the joint 4 in this case being provided with an externally threaded sleeve 23 seated in the shank 21 and adapted to receive the section 22, which is internally threaded at one end. A head 24 may be

brazed or fastened to the section 22 in any desired manner, and a temporary head 25 may be provided with a suitable threaded extension 26 for engagement with section 22. A temporary head for the section 21 70 (not shown) may be provided with an internally threaded hole to screw on the sleeve 23.

As shown in Fig. 7, a tubular needle of the general character of that shown in Fig. 75 5 may have a joint between a shank section 21 and a transfer section 22 constructed for frictional engagement, for instance, by providing the section 22 with a plug 28 brazed or fastened in place so as to enter the bore 80 in the section 21 when the parts are assembled. Suitable temporary heads 27 provided with plug members 28 may be provided for the needle or the transfer section. As many such joints as desired may be provided 85 in the length of the needle.

Another construction is shown in Fig. 8, the end of the section 21 being bored out to a taper, to receive the swaged end 29 of the section 22. If desired, the smooth outer 90 surface of the needle may be maintained by mounting on such a swaged section a shoulder-collar 30 against which the section 21 bottoms. The collar 30 may be applied as shown in dotted lines, and then ground 95 away to conform to the cylindrical surface of the needle. Temporary heads for the form shown in Figs. 7 and 8 may, as shown in Fig. 9 at 31, be provided with suitable openings 32 to receive the male member of 100 the friction coupling.

As shown in Fig. 10, for some classes of work it is possible to provide permanent heads for the shank 1, and one or more removable sections 3, for instance, by providing a globular enlargement 33 transversely divided at the joint 4. Loose knitting can be slipped over the enlargement 33 on to the section 3, and the needle then divided. Any suitable joint structure, as 110 the screw joint indicated at 34, may be employed with this construction.

A typical use of the device is illustrated in Fig. 11, in which a sleeveless sweater blank knit in the direction of the arrow 115 is shown. The operator will first knit a ribbed section *a* for the front blank *b*. When this has reached a sufficient length at the line *c* the loops from *d* to *e* may be taken off and suspended or the loops from *d* to *f* 120 fastened off and the loops from *f* to *e* taken off the needle and suspended, as indicated by the section 3 shown in dotted lines.

The loops from *c* to *d* remain on the needles, and the narrowed and widened shoulder section *g* is next made to the line *h*, whereupon the terminal course of this section may be suspended and knitting for the section *i* for the other shoulder resumed. It will be understood that the loops from 130

f to *e*, for instance, can be returned to an empty or full needle by applying the section 3 to the needle and slipping them on to shank 1.

5. What I claim is:—

1. A knitting needle having a shank and a transfer section adapted to be disengaged from or engaged with the shank while carrying loops formed on the shank of the 10 needle.
2. A knitting needle having a shank section and a transfer section, and means for joining said sections together so that loops on one section may be slid onto another section, the last mentioned section being adapted to retain the loops when separated from the other section.
3. A knitting needle comprising a shank section and a loop-carrying transfer section 15 adapted to be joined together and separated, and a head member adapted to be attached

to one of said sections when the other is removed.

4. A knitting needle having a removable loop-carrying transfer section and a temporary head for the needle adapted to be carried by said transfer section when not in use.

5. A knitting needle having a shank section and a removable transfer section adapted to receive loops formed on the shank section, said sections respectively being provided with the engaging parts of a friction joint adapted normally to hold said sections together in longitudinal continuity, 35 and being readily separable, whereby to remove with one of said sections a series of loops formed on the needle upon which knitting is temporarily suspended.

Signed by me at Boston, Massachusetts, 40
this tenth day of September, 1917.

KARL W. P. REECE.
